[57] CLAIM

The ornamental design for a telescopic magnetic screw starter, as shown and described.

DESCRIPTION

FIG. 1 is a perspective view of the telescopic magnetic screw starter according to the present invention;

FIG. 2 is a top plan view;

FIG. 3 is a side elevation view;

FIG. 4 is a bottom view;

FIG. 5 is a side elevation view showing the opposite side from that shown in FIG. 3;

FIG. 6 is an enlarged end view showing the screw holding device;

FIG. 7 is an enlarged end view from the opposite end shown in FIG. 6 showing the magnet end of the invention;

FIG. 8 is a elevational view of the telescopic magnetic screw starter shown in the extended condition; and

FIG. 9 is an enlarged cross-sectional view taken along the lines 9—9 of FIG. 5 showing the triangular shape of the body segments.
